(**) Term: **14 Years**

(57) **CLAIM**

(21) Appl. No.: **29/253,058**

I claim the ornamental design of a cover for a book or similar article, as shown and described.

(22) Filed: **Jan. 31, 2006**

DESCRIPTION

(51) **LOC (8) Cl.** 19-04

FIG. 1 is a front perspective view of a cover for a book or similar article, showing my new design, and illustrating the cover in an exemplary closed position over the exemplary environmental structure of the book;

(52) **U.S. Cl.** **D19/26**

FIG. 2 is a front elevational view thereof;

(58) **Field of Classification Search** D19/32,

FIG. 3 is a rear elevational view thereof;

D19/27, 26; D3/247, 276, 201, 249, 273,

FIG. 4 is a left side elevational view thereof;

D3/294, 274, 243, 245; 281/29, 38, 27.3,

FIG. 5 is a right side elevational view thereof;

281/15.1; 402/3, 4, 31, 19; 206/581, 472

FIG. 6 is a top plan view thereof;

See application file for complete search history.

FIG. 7 is a bottom plan view thereof;

(56) **References Cited**

FIG. 8 is a front perspective view of the cover illustrating the cover in an exemplary open position relative to the book;
